FRANK L. MORSE, OF ITHACA, NEW YORK

DOOR-OPERATING MECHANISM

Application filed August 26, 1926. Serial No. 131,565.

This invention relates to door operating mechanisms, and is, in part, a continuation, and, in part, a division of my application, Serial No. 64,590, filed October 24, 1925, on power actuated doors, certain features of its subject matter being disclosed especially in Figures 1 to 4 of that application.

One of the primary objects of my invention is the provision of an improved mechanism for opening and closing doors by power, which is simple, rugged, and compact; convenient and reliable in use and operation; and relatively inexpensive to manufacture.

Another object of the invention is the provision of an improved mechanism for operating large double doors employing a single power developing means.

Still another object of the invention is the provision, in an actuating mechanism, for double doors, of means for causing one door to be closed in advance of the other.

The above, as well as such other objects as may hereinafter appear, I obtain by means of a construction which I have illustrated in 25 preferred form in the accompanying drawings, wherein—

Fig. 1 is a fragmentary plan section through the upper door frame with my improved operating mechanism appearing in 30 plan view, the complete operating parts for the right hand door only being shown and the open position of this door being indicated in dotted lines;

Fig. 2 is a fragmentary sectional view 35 taken on the line 2—2 of Fig. 1;

Fig. 3 is an enlarged detailed section taken on the line 3—3 of Fig. 1;

Fig. 4 is an enlarged detailed section, 40 through a swivel nut and pivoted arm which I employ, taken on the line 4—4 of Fig. 1;

Fig. 5 is a plan section similar to Fig. 1, but showing my invention applied to a pair of single leaf outwardly opening swinging doors, the figure also embodying a modification;

Fig. 6 is a view similar to Fig. 5, but showing one of the doors closed and the other slightly open; and

Fig. 7 is an enlarged detailed section taken 50 on the line 7—7 of Fig. 5.

Referring to Figs. 1 to 4, inclusive, it will be seen that I have shown my invention applied to a pair of two leaf doors A and B, the complete connections to the door A, however, only being shown to simplify the drawings; it being understood that the connections to the door B are the same as for the door A. The first leaf of the door A is designated by the numeral 7 and the second leaf by the numeral 8, which leaves are hinged together 55 so as to fold on themselves when the door is opened as indicated in dotted lines in Fig. 1.

Connected to each door is an arm 9 which is pivoted at 10 on the bracket 11, said bracket being secured to the building structure 12 at a point adjacent to the door hinge 13. The free end of the arm 9 is connected to the second leaf 8 of the door by means of the link 14. By virtue of this arrangement it will be seen that the doors can be operated with 60 a minimum amount of power, and that the hinges are relieved of operating thrusts, the same being transmitted mainly to the pivot 10.

Each arm 9 is provided with a yoked portion 15 for receiving the swivel nut 16, into which nut is threaded the operating rod 17, the actuation of which will be hereinafter described. It is to be noted that the rod 17 extends from one pivoted arm 9 to the other, and that said rod, at one end, is threaded into the swivel nut of one arm, and, at the other end, into the swivel nut of the other arm, the threads of the rod and nut being opposite at opposite ends, that is to say, one end is provided with left hand threads and the other end with right hand threads.

As will be seen in Figs. 1 and 2, I have mounted a motor device C on the upper door sill 18 central of the door opening, which motor device comprises an electric motor 19 mounted on the base plate 20, and worm gearing 21, the worm of which is secured to the motor shaft, and the worm wheel 22 of which is mounted in the bearings 23, 23 formed, in this instance, as part of the base plate 20.

In this connection, it is pointed out that by virtue of the worm drive just described, the doors will be locked upon cutting off the 100

source of power. This not only acts as a safeguard against unauthorized opening of the doors, but also serves to hold the doors rigidly in their open position.

5 The worm wheel 22 is provided with a square hole 24 whereby it is adapted to fit the squared portion 24a of the operating rod 17, which portion 24a is somewhat longer than the worm wheel 22 is wide, thus making it possible for the rod 17 to move longitudinally within the limits of the stop nuts 25, 25, provided on the rod, and this for a purpose to appear hereinafter.

Assuming, now, that the doors are closed, 15 and it is desired to open them, the motor is started, by means of a suitable switch, which actuates the operating rod 17, rotating it, and causing the swivel nuts 16 to move outwardly by virtue of the right and left hand 20 threads previously described, which, in turn, causes the arms 9 to swing on their pivots, thus opening the door. Owing to the arcuate movement of the yoke 15, to which the nut 16 is swiveled, it is obvious that some 25 sort of compensating connection must be provided between the nut and the motor device to take care of this arcuate movement, and, as a simple and effective compensating means, I have provided the rod 17 with flexible portions 26, 26 at either side of the squared portion 24. In this instance the flexible portions 26, 26 are formed by flattening the rod into ribbon form at this point and then by giving the ribboned portion a 30 90° twist. Thus, it will be seen that the rod may be rotated by the motor device and also moved about the flexible portion as a pivot to compensate for the arcuate movement above described.

40 It is pointed out that if one door closes in advance of the other, the swivel nut in the arm of the closed door will then remain stationary, and the rod 17 will be moved longitudinally because it will then screw into the nut, thereby continuing the movement of the 45 other door until it reaches its closed position. The arrangement of worm wheel 22, rod 17 and stop nuts 25 permits of the above action.

50 In order to prevent jamming of the door, guide rails 27 are provided for the rollers 28 on the doors, which rails are curved inwardly at their ends toward the door hinges for the purpose of separating the leaves of 55 the door when the door is moved from open to closed position, thus preventing jamming.

Referring now to Figs. 5, 6 and 7, it will be seen that I have shown my invention applied to a pair of outwardly opening doors 60 D and E in which the long lever arms 9 are replaced by much shorter arms 9a, 9a, which arms are connected to the doors through the medium of the links 9b, 9b. It is obvious that here the nuts 16, 16 move toward the motor 65 device for opening the door and away from

it for closing the door, which is opposite to the movement for inwardly swinging doors.

It is to be noted that in these figures I have shown a modification of the motor device now to be described, although the motor device, 70 as shown in Figs. 1 to 4, may be employed, if desired.

When employing doors of the type shown in Fig. 5, it is customary to provide one of the doors with an astragal which, in this instance, is shown on the right hand door D, as viewed in Fig. 5, and designated by the reference numeral 29. In doors of this construction, it is, therefore, important that the door not carrying the astragal, in this case, door E, closes first, and that the door D, carrying the astragal, closes second, so as to prevent interference between the astragal and the face of the door E. To insure such closing of the doors at all times, I have provided a 80 spring 30 between a hub of the worm wheel 22 and a stop nut 25, which causes the operating rod 17 to be positively moved longitudinally on operation of the device to obtain the desired result.

In the particular embodiment shown, the spring 30 acts against the left hand stop nut 25 to move the operating rod to the left, the operation being as follows: Assuming, now 90 that both doors are closed, and the operating rod 17 in the position shown in Fig. 5, and that the motor is run in a direction to open the doors, then the first action is to rotate the rod which immediately begins to shift to the left, due to the spring tension, and continues to so shift until the right hand nut 25 comes up against the adjacent hub of the worm wheel. In so doing the rod screws into the left hand nut, and the door E is held closed. At the same time, due to this movement of 100 the rod and the inward creeping of the right hand nut 16, the door D opens. From this point on the two doors open together, the door D, however, maintaining its lead on the door E. The amount of lead one door has 110 over the other is determined by the amount of lost motion provided at 25a. In Fig. 6 this lead has been exaggerated, but it is to be understood that the amount thereof may be altered to suit any particular case. If 115 desired, the nuts 25 may be made adjustable to adjust the amount of lead. Stops may be provided to limit the opening movement of the doors, which may be arranged so that the door D strikes its stop first to take up the 120 lead above mentioned. When the doors assume their full open position, the motor may be automatically or otherwise stopped.

To close the doors, the motor is rotated in the opposite direction, which again causes 125 the operating rod to shift to the left, assuming that the lead on opening was taken up, which causes the door E to take the lead, and to maintain its lead until it reaches its full closed position (see Fig. 6). As the mo- 130

tor device continues to rotate, the rod 17 screws out of the left hand nut 16, thus shifting the rod to the right against the tension of the spring, which action, together with the right hand nut creeping outwardly on the rod, closes the second door, and the rod 17 again assumes the position shown in Fig. 5.

From the above, it will be seen that I have provided a means for insuring the closing of one door in advance of the other, thus avoiding any danger of interference between the astragal and the face of the mating door. Binding or interference is also avoided when opening the doors.

15 I claim:—

1. A door operating mechanism comprising, in combination, a motor, a pivoted arm, the free end of which is connected to the door, a swivel nut carried by said arm, and 20 a driving rod between said motor and said arm having threads for engagement with the swivel nut, and having a flexible ribbed portion.

2. An operating mechanism for a pair of 25 doors comprising, in combination, a pair of pivoted arms, each connected at its free end to its adjacent door, a motor, and a compensating driving connection between said motor and said arms adapted to compensate for 30 the arcuate travel of the arms at the point of connection and for the closing of one door in advance of the other, together with means associated with said compensating driving connection for insuring the closing of one 35 door in advance of the other.

3. A door operating mechanism for a pair of doors comprising, in combination, lever means associated with each door for opening and closing the doors, and means for operating said lever means, including a motor, an operating rod rotatable by said motor, means operatively connecting said rod with the aforesaid lever means, and spring means operating on the rotatable rod to cause one door 45 to be closed in advance of the other.

4. An operating mechanism for double 50 doors comprising, in combination, a motor, an operating lever arm for each door, an operating rod connecting said lever arms, oppositely threaded connections between said arms and said rod, the connection between said motor and said rod having capacity for lost motion in order to compensate for one door closing in advance of the other.

5. An operating mechanism for double 55 doors comprising, in combination, an operating lever arm for each door, an operating rod connecting said lever arms, oppositely threaded connections between said arms and said rod, and a motor device for rotating said rod, the connection between said motor device and said rod having capacity for lost motion, together with spring means operating to take up said lost motion to insure the 60 closing of one door in advance of the other.

6. An operating mechanism for double doors comprising, in combination, an operating lever arm for each door, an operating rod connecting said lever arms, threaded connections between said arms and said rod, a 70 motor device for rotating said rod, a connection between said motor device and said rod whereby the rod may move longitudinally while being rotated by the motor device, means for causing the rod to be so moved, 75 and stop means limiting the amount of such movement.

In testimony whereof I have hereunto signed my name.
